UNITED STATES PATENT OFFICE.

FRANK D. SMITH, JR., OF WASHINGTON, DISTRICT OF COLUMBIA.

AUTOMATIC-STOP CONTROL FOR TESTING MACHINES.

Application filed March 8, 1926. Serial No. 93,179.

This invention relates to an automatic stop for tensile testing machines and is designed to stop or to stop and reverse the motion of the machine at the breaking of the test piece. It can be adapted to machines of either the horizontal or vertical type although the vertical type only is shown in the accompanying drawings. The device is especially applicable to the type of machine disclosed in the patent to H. L. Scott Number 1,324,470.

The general operation of the machine consists in clamping a test piece between two clamps, the upper clamp being operatively connected to a dial and the lower clamp being connected to a tension applying screw. A worm gear having an internal screw thread is revolved about the tension screw by means of suitable gearing and thus tension is applied to the piece until a break occurs. When the breakage occurs it is necessary to reverse the drive and return the lower clamp so as to receive another test sample.

In the preferred machine there is a reciprocable rod for controlling the mechanism which performs this function. The rod may at present be moved by hand or it may be moved by the bracket on the test screw when a predetermined lower limit is reached. The first method requires the attention of the operator and the second consumes an excessive amount of time before it operates, especially if the break occurs at a distance above the lower limit stop.

The purpose of this invention, therefore, is to cause the rod to be moved automatically at the instant of the breakage of the test piece, regardless of the attention of the operator or where the break occurs.

The details of how this is done will appear in the course of the following description.

In the drawings, in which like numerals represent the same or similar parts:

Figure 1 shows a side view of the vertical type of machine with the improvement in use.

Figure 2 is an enlarged side view of one form of my invention.

Figure 3 is a section on line 3-3 of Figure 2.

Figure 4 is a section on line 4-4 of Figure 2.

Figure 5 is a detail of the friction cylinder.

Figure 6 is a detail of the lever mounting.

Figure 7 shows an electrical modification. Figure 8 shows a variation of parts of the device shown in Figure 7.

Referring to Figure 1 the letter A designates the dial portion of the machine; B the lower clamping means and my improvement; and C the driving mechanism for the machine.

In the drawings 10 is the clamp for the lower portion of the test piece 11. Clamp 10 is connected by means of rod 12 to lever 13 which is pivoted on rod 14 to main support 15 which is carried by screw 16. Support or bracket 15 has a circular opening 17 enabling it to slide freely upon rod 18. An adjusting screw 19 bears on lever 13 at 20 and limits the movement of the lever as tension is applied to test piece 11. Lever 13 has an enlarged portion 21-21'. The enlarged portion consists of 21' integral with lever 13 and 21 removably fastened to 21' by screws 26.

At suitable positions on rod 18 collars 23 and 24 are fastened. When support 15 strikes collar 24 the driving mechanism for screw 16 is stopped or preferably stopped and reversed, and when portion 21 of lever 13 strikes collar 23 the driving mechanism is disconnected from screw 16. These operations are performed by vertical reciprocation of rod 18 operating in gear box C, but as this forms no part of my invention it will not be further described.

The method of pivoting lever 13 is best shown in Figure 6. Trunnion 29 has screw threaded hole 28 to receive screws 34 and thus make it removable from bracket 15. Adjustment of the lever with respect to rod 18 is obtained by means of moving screws 34 in slots 33 in bracket 15.

A spring 30 is provided if desired to aid in the movement of the lever 13 when in operation. This spring is fastened to lever 13 at 31 and to bracket 15 at 32. The spring is most desirable in the horizontal type of machine.

I prefer to cut the cylinder 22 as shown at 22' in Figure 5 to enable it to be placed about rod 18 and in the holder 21-21' without removing the rod. Any suitable material can be used for cylinder 22 such as rubber or leather, or portions 35 and 36 may be suitable knurling on the inside of 21-21'. I prefer to use a removable cylinder of rubber as shown in Figure 5.

By providing screw 27 the automatic stop

may be rendered inoperative to permit special or fatigue testing. When screws 27 and 19 are both in contact with lever 13 it is clear that movement of the lever is prevented.

A spring 37 is coiled about rod 18 and is freely movable thereon. In the upper or stop position this spring compresses about an inch and a half before motion ceases. Thus the lever 13 cannot pivot to the right upon starting until after about an inch of travel and by this time the tension on piece 11 holds lever 13 up.

In Figures 2 and 4 I have shown a preferred form of clamp mounting. This mounting gives a straight line motion to the clamp when the device operates. Lever 13 is slotted as shown at 57 and in this slotted portion is placed rod 12 of clamp 10. Bracket 15 has a circular hole 58 bored therein, the upper portion of which is threaded as at 59' to receive apertured limit plug 59. Rod 12 has an enlarged piston like portion 61 which fits snugly in hole 58 but is prevented from pulling out of the hole by the limit plug 59. Pin 62 is mounted on rod 12 and is movable in slot 63 of lever 13. Where straight motion of the clamp is not necessary it may be mounted directly on lever 13 as shown in Figure 7.

The operation of this modification is as follows:

When tension on test piece 11 is removed due to breakage, the weight of the clamp 10 and if desired, the added tension of spring 30 causes lever 13 to rotate to the right. As a result, portions 35 and 36 of cylinder 22 bear frictionally upon rod 18 and carry it downward causing the driving motion to reverse and move bracket 15 and attachments, upward. By means of screw 19, cylinder 22 is prevented from gripping rod 18 on the upward travel. At the top of the journey, holder 21 will strike collar 23 and so stop the machine, making it ready for the next test. Thus the motion is reversed automatically regardless of where the break occurs.

When fatigue testing is desired, that is when the piece is to receive a number of tension applications, the machine is run a distance in one direction and is reversed, this being repeated until the piece receives a certain number of tension applications or until a break occurs. This reversal is performed by the bracket striking the collars, and to give the clamp the necessary rigidity it is best to turn up screw 27 thus preventing movement of lever 13.

In the modification shown in Figure 7, an electric means is used to actuate the reversing rod when the test piece breaks. The general structure is the same as in the previous modification so an additional description will not be given. Fastened to

lever 13 and insulated therefrom by insulation 38 is one part of a knife switch 39. The other part, 40, is mounted on the bracket 15 by means of insulation 41. A suitable wiring 42 is connected to switch element 39 and through battery 43 to a switch element 44 mounted on the frame of the testing machine. Another switch element 45 is fastened to rod 18 and has wire 46 leading to solenoid coil 47. Wire 48 leads from solenoid coil 47 to switch element 40 and completes the circuit.

The operation of this modification is as follows:

Rod 18 is lifted so as to cause the driving mechanism to give a downward motion to tension screw 16. This raising is done by means of a lever (not shown) attached to the machine. To better illustrate the positions of rod 18 for various operations, I have suggested a pointer 49 fastened to the rod. The drawings show a set for having screw 16 at a standstill. Raising the rod gives a downward motion to the tension screw and lowering the rod gives an upward motion. When the rod is raised switch 44, 45 closes. Switch 39, 40 does not close, however, due to the compression in spring 37 holding lever 13 horizontal. By the time spring 37 ceases to function, sufficient tension occurs in the test piece and this tension serves to hold the lever horizontal. When a break occurs, lever 13 pivots to the right and switch 39, 40 closes thus energizing solenoid 47. Rod 18 becomes the core of the solenoid and is pulled down by it, causing a reversal of the driving mechanism, and causing the screw 16 to move upwards. As rod 18 is pulled down switch 44, 45 is opened and solenoid 47 is deenergized allowing bracket 15 to return, without actuating rod 18 on the upward travel until collar 23 is reached.

A further modification of the above is shown in Figure 8 in which closed mercury switches are used in order to prevent sparking. Rod 18 carries bracket 49 which has roller 50 journaled therein. When the rod is raised, roller 50 raises lever 51, pivoted at 52 to the frame, and causes mercury 53 to fill the short leg of sealed tube 54 and make contact between switch elements 44' and 45'. When a break occurs, lever 13 tilts to the right and mercury 55 fills short leg of tube 56 making contact between switch elements 39' and 40', which energizes solenoid 47 as above.

Any of these modifications will operate should the piece slip out of the clamp prior to breakage.

In case the device is to be used with a hydraulic machine, rod 18 may be connected to a valve and so arranged as to set the valve in inlet, exhaust or neutral position. Many changes are possible without de-

parting from the spirit of the invention, when the limit of movement of the tension member in one direction has been reached. and I limit myself only to the extent of the claims which follow.

I claim:

5 1. In a testing machine of the class described, the combination of means for applying tension to a piece of goods, operating means for said tensioning means, control means for said operating means, a bracket mounted on said tensioning means, and a lever to operatively connect said bracket to said control means.

10 2. In a testing machine the combination of means for applying tension to a piece of goods, operating means for said tensioning means, control means for said operating means, a bracket mounted on said tensioning means, and a lever mounted on said bracket to operatively connect said bracket to said control means.

15 3. In a testing machine, the combination of means for applying tension to a piece of goods, operating means for said tensioning means, control means for said operating means, a bracket mounted on said tensioning means, and a lever removably and adjustably mounted on said bracket to operatively connect said bracket to said control means.

20 4. In a testing machine, the combination of means for applying tension to a piece of goods, operating means for said tensioning means, control means for said operating means, a bracket mounted on said tensioning means, and a lever pivotally mounted on said bracket to operatively connect said bracket to said control means.

25 5. In a testing machine, the combination of means for applying tension to a piece of goods, operating means for said tensioning means, control means for said operating means, auxiliary means mounted on said tension applying means to actuate said control means and means to maintain said auxiliary means disconnected from said control means when the tension member moves in one direction.

30 6. In a testing machine, the combination of means for applying tension to a piece of goods, operating means for said tensioning means, control means for said operating means, auxiliary means mounted on said tension applying means to actuate said control means, and an adjustable screw to maintain said auxiliary means disconnected from said control means when the tension member moves in one direction.

35 7. In a testing machine, the combination of means for applying tension to a piece of goods, operating means for said tensioning means, control means for said operating means, auxiliary means mounted on said tension applying means to actuate said control means and means to hold said auxiliary means disconnected from said control means

40 when the limit of movement of the tension member in one direction has been reached.

8. In a testing machine, the combination of means for applying tension to a piece of goods, operating means for said tensioning means, control means for said operating means; auxiliary means mounted on said tension applying means to actuate said control means, means to hold said auxiliary means disconnected from said control means when the limit of movement of the tension member in one direction has been reached, and means to maintain said disconnected relation during a small tensioning movement of said tensioning means.

45 9. The structure as set forth in claim 8, and said last named means being inoperative after said small tensioning movement has taken place.

10. In a testing machine, the combination of means for applying tension to a piece of goods, operating means for said tensioning means, control means for said operating means, auxiliary means mounted on said tension applying means to actuate said control means, means to hold said auxiliary means disconnected from said control means when the limit of movement of the tension member in one direction has been reached, and a spring to maintain said disconnected relation during a small tensioning movement of the tension applying means.

50 11. In a testing machine, the combination of means for applying tension to a piece of goods, operating means for said tensioning means, control means for said operating means, and auxiliary means set in operation upon the removal of tension in the piece of goods to operatively connect said control means to said tension applying means.

55 12. In a testing machine, the combination of means for applying tension to a piece of goods, operating means for said tensioning, a reciprocable rod to control said operating means, a bracket mounted on said tensioning means, a lever pivotally mounted on said bracket, said lever being controlled at one end by a clamp which holds the goods, the opposite end of the lever comprising an enlarged portion with an aperture therein which surrounds said rod, said aperture being of such size as to slide freely on said rod when there is tension in the goods but small enough to bind on said rod when tension is removed and the lever rotates, whereby the rod is connected to the bracket.

60 13. The structure set forth in claim 12 and in addition means to aid said lever in connecting said rod and said bracket.

65 14. The structure set forth in claim 12 and a spring to aid in connecting said rod and said bracket.

15. The structure of claim 12 and a cylinder mounted in said enlarged portion.
16. The structure of claim 12 and a yielding cylinder mounted in said enlarged portion.
17. The structure of claim 12 and a rubber cylinder mounted in said enlarged portion.
18. The structure of claim 12 and a cylinder mounted in said enlarged portion, said aperture having circumferential grooves and said cylinder having ridges to fit said grooves.
19. In a testing machine, the combination of means for applying tension to a piece of goods, operating means for said tensioning means, control means for said operating means, auxiliary means to actuate said control means, a clamp mounted to control said auxiliary means and means to restrict the motion of the clamp to a straight line.
20. In a testing machine the combination of means for applying tension to a piece of goods, operating means for said tensioning means, control means for said operating means, a bracket mounted on said tensioning means, auxiliary means to operatively connect said bracket to said control means, a clamp to control said auxiliary means, a rod on said clamp and a hole in said bracket, said rod being mounted in said hole.
21. In a testing machine having a shift rod with limit collars to reverse and stop a tension applying means and having a bracket on said tensioning means, movable on the shift rod to engage said collars; auxiliary means to operatively connect the bracket to the shift rod when the tension in the piece is removed.
22. The structure of claim 21 and means to mount said auxiliary means on the bracket.
23. The structure of claim 21 and means to prevent said bracket being operatively connected when the tensioning means moves in a predetermined direction.
24. The structure of claim 21 and means to render said auxiliary means completely inoperative.
25. The structure of claim 21 and means to render said auxiliary means inoperative during a small initial tensioning movement of the tensioning means.
26. The structure of claim 21 and a spring loosely coiled about the shift rod, said spring rendering said auxiliary means inoperative during a small initial tensioning movement of the tensioning means.
27. The structure of claim 21 and a lever pivotally mounted on the bracket, said lever being controlled by a clamp for the goods at one end and having an enlarged portion at the opposite end, said enlarged portion having an aperture freely movable on the rod when the lever is in one position, said aperture being of such size as to bind on the rod when the lever is in any other position.
28. In a testing machine having a shift rod with limit collars to reverse and stop a tension applying means and having a bracket on said tensioning means movable on the shift rod to engage said collars; a lever, means to mount said lever on the bracket, said lever being controlled by a clamp at one end and having an enlarged portion with an aperture adapted to surround the rod, and a cylinder removably mounted in said aperture.
29. The structure of claim 28 and said cylinder being made of a yielding material.
30. The structure of claim 28 and said cylinder being made of vulcanized rubber.
31. The structure of claim 28 and said aperture having circumferential grooves, and said cylinder having ridges to fit said grooves.
32. In combination, a lever, an apertured portion at one end of said lever, a trunnion pivoted to said lever and adapted to be mounted on a bracket, and means to connect a clamp to said lever opposite to said apertured end, all for the purpose set forth.

FRANK D. SMITH, Jr.
